FIG. S.

UNITED STATES PATENT OFFICE

2,279,271

WINDOW UNIT SIDE WING CONSTRUCTION

Burdell S. Williams, Dayton, Ohio, assignor to
 Chrysler Corporation, Detroit, Mich., a corpora-
 tion of Delaware

Application May 6, 1940, Serial No. 333,516

3 Claims. (Cl. 98—94)

The present invention relates to the construction of side wings for blocking the openings left between the ledge and sides of a window frame, the bottom of the lower sash of a vertically movable window and the sides of a window ledge air conditioning unit placed on the ledge of a window. The present invention is an improvement on existing structures for blocking the openings at the sides of the unit and may be used in conjunction with any air conditioning unit of the foregoing type which is smaller than the opening in which the unit is placed, but it achieves particular utility in connection with a unit mounted in accordance with the disclosure of my copending application filed concurrently herewith, Serial No. 333,515.

In particular, the invention comprises a folded or plaited member which may be expanded or contracted to accommodate different sizes of openings whereby the side wings may be manufactured in quantities for use in connection with many different sizes of windows. Specifically, the invention comprises an air impervious member having reentrant folds or corrugations, the member being rigid enough to maintain its shape in use but being relatively yielding to longitudinal compression or extension so as to be readily fitted to various sizes of window openings. In connection with the foregoing it is an advantage of the present construction that the side wing may be folded, rolled or compressed into a very small space so as to minimize the size of the carton required to accommodate the unit and the appurtenances thereto.

The present invention may be more readily understood by reference to the accompanying drawing wherein like numerals refer to like parts throughout.

In the drawing, Fig. 1 discloses a window ledge air conditioning unit in the position of use and having the present invention associated therewith;

Fig. 2 is a horizontal section taken substantially along line 2—2 of Fig. 1 looking in the direction of the arrows;

Fig. 3 is an isometric view of a modified form of side wing;

Fig. 4 is a similar view of another modified form of side wing; and,

Fig. 5 is a similar view of another modified form of side wing.

Referring to Figs. 1 and 2, there is disclosed a window frame 10 in which is provided an upper window 11 and a lower, vertically movable window 12 having a lower sash member 13. The window

ledge type air conditioning unit 14 is supported upon the window ledge 15 and is shown as attached to a bar 16 by a clevis strap 17, the bar 16 being pivotally mounted upon a pivot post 18 fastened to the top of the window ledge near the right lower corner of the window opening. A strap 19 is suspended from a hook 20 substantially vertically above the post 18 and is provided with a hook 21 at its lower end which may be engaged with an eye 22 fastened to the unit at the upper left edge thereof. The bar 16 and strap 19 provide means whereby the unit may be swung into the room in accordance with the disclosure of the aforesaid copending application. It is to be noticed that the strap 19 is shorter than the distance between hook 20 and eye 22 so that the outer edge of the unit is raised clear of the window ledge to permit swinging movement, and that the post 18 is provided with a lever 23 and cam 24 by means of which the right side of the unit may be raised clear of the window ledge. As shown in Fig. 2, a pair of straps 19 and a pair of eyes 22 are preferably provided. Also, Fig. 2 shows a condenser air deflecting hood 25 which is hinged at 26 so as to be capable of being pivoted onto the top of the unit to permit swinging thereof through the window opening when the window 12 is raised.

The present invention comprises a pair of side wing members 30, one of which may be mounted at the right side of the unit and remain fixed in position during swinging of the unit, and the other of which is mounted at the left side of the unit and may be removed to permit swinging movement of the unit. Each member 30 comprises a plurality of vertical panels 31 hinged together as by means of reentrantly folding or plaiting a flat sheet of material. The member may be shipped in collapsed state and then opened to the desired extent at the place of use so as to fit within the sash guides with the folds thereof extending vertically between the window ledge and the bottom sash 13. The material may be of sufficient resiliency to be stretched to a length greater than the desired space, so that when inserted in the space it will exert pressure against the side of the unit and the side of the window opening. Preferably, a strip of sponge rubber 32 is placed on the window ledge and another strip of sponge rubber 33 is placed between the sash 13 and the top of the member 30 so as to seal the edges of the opening. It is readily obvious that the member 30 at the left side of the unit may be compressed and extracted from the space it occupies during use in

order that the unit may be pivoted into the enclosure.

The material of which the members 30 is composed may comprise thin metal stock decorated to harmonize with the room, or plated with a non-corrosive metal, or may comprise any of certain fibrous or plastic materials which have the desired characteristics described previously. In addition, the material may be such, as in certain plastics, as to be translucent or transparent so as to permit the passage of light through the material into the room.

The modification disclosed in Fig. 3 shows vertical panel portions 31 provided with pintel receiving bends 35 at their edges which are adapted to receive pintel members 36. Preferably, the hinges so formed are reversed in position as shown in Fig. 3 so that alternate hinges are inside of the bends and the other hinges are outside of the bends of the side wing so that the side wing may be collapsed to a certain extent by reverse folding but, when stretched out to its fullest longitudinal direction, will resist compression longitudinally. Preferably, the material is resilient so that the vertical panel portions 31 will bend thereby permitting compression longitudinally into a smaller space than would normally be occupied in order that the side wing will exert pressure against the side of the unit and the side of the window opening.

In Fig. 4 the side wing is shown as comprising vertical panel portions 31 of very narrow width and at the junctions of reversely curved portions 40, the side wing being thus a corrugated panel which may be rolled upon itself during shipment and may be collapsed to more or less extent longitudinally in order to accommodate different sizes of openings.

In the modification of Fig. 5 the vertical panel portions 31 are similar to the form shown in Figs. 1 and 2, except that the bends between the panel portions are formed around vertical, reinforcing rods 45 which give vertical rigidity to the side wing. The rods 45 may be held in place solely by the gripping action of the bends between the panels or may be otherwise fastened therein.

Having described several modifications of the present invention, it should be apparent to those skilled in the art that the same permits of various modifications in arrangement and detail. All such modifications as come within the scope of the following claims are considered to be a part of my invention.

I claim:

1. The combination with a window ledge air conditioning unit mounted in the position of use

on a window ledge beneath the lower sash of a vertically movable window of a side wing blocking the opening at the side of the window between the window ledge and the lower sash of a vertically movable window, said side wing comprising a member having folds therein defining a plurality of vertically extending panel portions, said member being of sufficiently rigid material to resist distortion to an extent sufficient to cause said member to exert pressure against the side of the window opening and the side of the window unit when inserted in the opening at the side of the unit.

2. The combination with a window ledge air conditioning unit mounted in the position of use on a window ledge beneath the lower sash of a vertically movable window of a side wing blocking the opening at the side of the window between the window ledge and the lower sash of a vertically movable window, said side wing comprising a corrugated member, the corrugations of which extend vertically when the member is in use, said member being of sufficiently rigid material to resist compression of the corrugations to an extent sufficient to cause said member to exert pressure against the side of the window opening and the side of the window unit when inserted in the opening at the side of the unit, but being pliable enough to permit compression of said corrugations in order that said member may be inserted in openings of various widths.

3. The combination with a window ledge air conditioning unit mounted in the position of use on a window ledge beneath the lower sash of a vertically movable window of a side wing blocking the opening at the side of the window between the window ledge and the lower sash of a vertically movable window, said side wing comprising a member having vertical folds therein defining a plurality of vertically extending panel portions, each of said panel portions being so formed at its edges as to embrace with the edges of adjoining panel portions, vertically extending rods imparting vertical rigidity to the member, said member being of sufficiently rigid material to resist compression tending to decrease the angles between adjacent vertical panels to an extent sufficient to cause said member to exert pressure against the side of the window opening and the side of the window unit when inserted into the opening at the side of the unit, but being pliable enough to permit longitudinal compression of the member to accommodate openings of various widths.

BURDELL S. WILLIAMS.
